UNITED STATES PATENT OFFICE

KARL M. HAMILTON, OF CHICAGO, ILLINOIS, ASSIGNOR TO THE BETTENDORF COMPANY, OF BETTENDORF, IOWA, A CORPORATION OF IOWA

RAILWAY CAR FLOOR DOOR

Application filed December 2, 1929. Serial No. 410,980.

This invention relates to railway car floor doors of the type which are hinged to swing downwardly to permit gravity discharge of loose material from the interior of the car.

5 It is the object of the present invention to provide a door of superior strength and durability which can be manufactured at a relatively low cost.

A further object of the invention is to provide 10 a door having a one-piece metal frame which has integral hinge members and latch-engaging arms projecting from opposite edges thereof.

A further object of the invention is to provide 15 a door having a one-piece metal frame which has integral hinge members and latch-engaging arms which are continuations of the longitudinal side members of the frame.

A further object is to provide a one-piece 20 metal door frame which has integral hinge arms projecting beyond the inner edge of the door, which are continuations of the longitudinal side members of the frame.

A further object is to provide a door in 25 which the floor boards forming the face of the door may extend longitudinally of the door in the direction of the flow of material over the face of the door during the discharge of material from the car.

30 With the foregoing and other objects in view, the invention may be said to comprise a door as illustrated in the accompanying drawings hereinafter described and particularly set forth in the appended claims, together with such variations and modifications thereof as will be apparent to one skilled in the art to which the invention appertains.

Reference should be had to the accompanying 35 drawings forming a part of this specification in which:

Figure 1 is a plan view of a portion of a car floor with a portion of the car flooring and a portion of the flooring forming the face of the door omitted to show the frame structure;

Fig. 2 is a section taken on the line indicated at 2—2 in Fig. 1;

Fig. 3 is a fragmentary side elevation of 50 the lower portion of the car with a portion

of the car wall and side sill omitted to show a portion of the outer edge of the door;

Fig. 4 is a side elevation of a door provided with a metal floor plate;

Fig. 5 is an end elevation of the door 55 shown in Fig. 4.

The accompanying drawings show the door of the present invention mounted to close an opening in the floor of a railway car, a portion only of the car structure being shown. The drawings show a portion of the floor 1 and a portion of the side wall 2 of a railway car, the car body being supported in the usual manner upon an under-frame composed of a longitudinal center sill 3, longitudinal side 60 sills 4, and cross beams 5 extending from the center sill to the side sills, one side only of the car structure being shown in the drawings.

As shown in Fig. 1 of the drawings, the car floor is provided with a door opening 6 65 located between the center sill 3 and the side sill 4, it being understood that the door opening 6 may be one of a series of door openings which are arranged along opposite sides of the center sill.

The door of the present invention is provided with a one-piece metal frame, preferably in the form of a steel casting, and this frame has side members 7 which may be of any suitable cross sectional shape and which 70 extend across the door from the inner to the outer edge thereof which preferably converge toward the outer edge of the door. The side members 7 as herein shown are provided with horizontally disposed top flanges 8 which extend inwardly. Adjacent the inner ends of the side members 7, the frame is provided with an inner member 9 of any suitable cross-sectional shape extending the full length of the inner edge of the door. The member 9 75 as herein shown has an inwardly projecting flange 10 lying in the plane of the flanges 8 of the side members and forming a continuation of the flanges 8, the inner member 9 having end portions 11 projecting outwardly of 80 the side member 7. Adjacent the outer ends of the side members 7 the frame is provided with an outer member 12 of any suitable cross-sectional shape extending the full length of the outer edge of the door, the 85

member 12, as herein shown, having an inwardly projecting flange 13 in the plane of the flanges 8 of the side members and continuous with the flanges 8. The outer frame member 12 has end portions 14 projecting outwardly from the side members 7, the flange 13 being extended beyond the side members to the outer ends of the outer frame member. The frame is preferably provided 5 with an intermediate cross member 15 of any suitable cross-sectional shape which, as shown herein, is T-shaped in cross section having flanges 16 at the top thereof continuous with the flanges 8 of the side members and lying in the plane of the flanges 8, 10 and 13. At the inner edge of the door integral inwardly projecting hinge arms 17 are provided, which are preferably extensions of the 20 side members 7. The hinge arms 17 are received between hinge butts 18 attached to the center sill 3 and are apertured to receive hinge pintles 19. At the outer edge thereof the frame is provided with projecting fastener engaging arms 20 which are formed integral with the frame and are preferably continuations of the members 7. In doors designed for cars having side sills below the 25 floor level, the arms 20 may be offset downwardly with respect to the body of the frame, having inner portions 21 extending downwardly and outer end portions 22 extending outwardly at right angles to the portions 21, the depth of the downwardly extending portions 20 being such that the outwardly extending portions 22 lie directly beneath the side sill 4 when the door is in closed position. The projecting portion 22 of each arm is 30 preferably box-shaped in cross section and of sufficient length to project somewhat beyond the outer face of the side sill 4, the outer end portions of the arm being angular in cross section and having inwardly projecting top flanges 23 adapted to be engaged by suitable 35 hooks or latches 24 which may be pivotally mounted on the side sill. The hooks or latches 24 are preferably formed with inclined lower end faces with which the flanges 23 engage as the door is raised to closed position to permit the flanges 23 to pass the hooks, which automatically swing to latching position to retain the door in closed position. The 40 flanges 8, 10, 13 and 16 of the frame members provide a flat upper face to which a suitable flooring may be attached. The flanges 10 and 13 of the inner and outer frame bars are provided with bolt holes 25 to receive bolts 26 for attaching the ends of floor boards 27 to 45 the cross members. It should be noted that the floor boards 27 extend from the inner to the outer edges of the door, so that material sliding over a door opened for discharging material slides lengthwise of the boards in the direction of the grain of the floor boards 50 and in the direction of the joints between

the adjacent boards, so that there is a minimum wear upon the floor boards due to the abrasive action of the sliding material.

The door may be faced with metal plates instead of floor boards and Figs. 4 and 5 of the drawings show a door with a metal floor portion, the frame as illustrated in Figs. 4 and 5 being substantially identical with that illustrated in Figs. 1, 2 and 3. In doors faced with metal plates the hinge arms and the latch 70 engaging arms may be offset downwardly to a greater extent with respect to the top face of the frame to bring the top surface of the door flush with the surface of the car floor. In this modification, the top face or floor portion of the door is formed by a metal plate 28 which may be welded or riveted to the flanges of the frame members, the plate 28 having down-turned side flanges 29 which fit over the ends of the cross-members 9 and 12, which serve to stiffen the edges of the plate. 80

It will be apparent that the present invention provides a very rigid door structure possessing great strength and durability, and, by reason of the fact that the hinge arms and latch engaging arms are both formed as integral parts of the frame casting, a considerable saving is effected in the cost of manufacture and installation of the door. 90

It will also be apparent that where wood flooring is employed for the face of the door the flooring is applied to the door in such manner that it is subjected to a minimum amount of wear due to the action of loose material sliding over the face of the door as it is being discharged from the car. 100

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims. 110

What I claim is:

1. In combination with a railway car having a center sill, a side sill and a floor having a door opening between the center and side sill, a door for closing said opening comprising a cast metal frame having inner and outer members and connecting members adjacent the ends thereof and integral therewith, said frame having integral hinge members projecting from one edge, integral fastener engaging and door supporting arms projecting from its opposite edge, and a floor portion of a size to fit in said opening attached to said frame. 115

2. In combination with a railway car having a door opening in the floor thereof, a door for closing said opening comprising a cast metal frame having members extending along the inner and outer edges of the door and outwardly converging members connecting 120

130

the inner and outer frame members and formed integral therewith, said frame having integral hinge arms projecting from its inner edge and forming extensions of said connecting members and integral fastener arms projecting from its outer edge and forming extensions of said outwardly converging connecting members.

3. In combination with a railway car having a center sill, a side sill and a floor having a door opening between the center and side sill, a door for closing said opening comprising a cast steel frame having members extending along the inner and outer edges of the door, and spaced connecting members integral with the inner and outer members, said inner frame member having hinge members integral therewith and said outer frame member having integral outwardly projecting arms forming extensions of the connecting members, said arms being offset downwardly to project beneath the side sill, and a floor portion of a size to fit in said opening attached to said frame.

25 4. A door for railway car floors comprising a cast metal frame having inner and outer members extending along the inner and outer edges of the door, integral connecting members converging toward the outer edge of the frame, said connecting members being connected to the inner member adjacent the ends thereof and to the outer member inwardly of its ends, outwardly projecting fastener arms integral with the frame and forming continuations of the connecting members, and floor boards resting on the upper faces of the frame members and attached at their ends to said inner and outer frame members.

40 5. A door for railway car floors comprising a one-piece frame composed of inner and outer frame members, spaced integral connecting members extending from the inner to the outer members and a floor portion secured to the top face of the frame, said spaced connecting members extending past said inner and outer frame members to provide integral hinge arms at the inner edge of the door and integral fastener arms projecting from the outer edge of the door.

45 6. A door for railway car floors comprising a one-piece frame composed of inner and outer frame members, spaced integral connecting members extending from the inner to the outer members and a floor portion secured to the top face of the frame, integral hinge arms at the inner edge of the door and integral fastener engaging and door supporting arms projecting from the outer edge of the door.

In testimony whereof I affix my signature.
KARL M. HAMILTON.
